UNITED STATES PATENT OFFICE

ARTHUR L. KLINE, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN

PAINTING INSTRUMENT

Application filed March 22, 1928. Serial No. 263,625.

This invention relates to painting instruments and more particularly to striping pencils.

Heretofore in the art of painting, and particularly in the art of painting vehicles, striping has been performed by hand and this method has been found not only slow and costly but altogether unsatisfactory owing to the lack of uniformity due to the personal equation entering into the work and the absence of suitable means whereby the work might be accomplished with mathematical precision. To overcome these objections is the aim of the present invention.

An object of the invention is to provide a striping pencil for painting a stripe on plain or curved surfaces.

Another object of the invention is to provide a striping pencil for painting stripes of uniform width.

Another object of the invention is to provide a striping pencil for painting stripes regardless of the plane in which the stripes may be positioned, that is, regardless as to whether the stripes are horizontal, vertical or inclined.

A further object of the invention is to provide a striping pencil having an automatic ejecting means operated by the movement of the pencil over the surface to be striped.

A further object of the invention is to provide a striping pencil having a chamber and an auxiliary chamber connected therewith and means in the auxiliary chamber for automatically ejecting fluid from the auxiliary chamber through a nozzle in a predetermined flow of uniform volume per unit area of work painted.

A further object of the invention is to provide a striping pencil having a chamber and an auxiliary chamber connected therewith, the auxiliary chamber having a nozzle and means therein for ejecting fluid from the auxiliary chamber through the nozzle, the

ejecting means being automatically operated by a rotatable guide for the pencil.

Other objects of the invention will appear from the following description taken in connection with the accompanying drawings, which form a part of the following specification, and in which:

Figure 1 is a top plan view,

Figure 2 is a side elevation, and

Figure 3 is a longitudinal sectional view.

Referring to the drawings for more specific details of the invention, 10 represents a chamber having formed integral and parallel therewith an auxiliary chamber 11. The auxiliary chamber 11 has arranged thereupon a boss 12, the object of which will hereinafter appear, and the chamber 10 has threaded in one end thereof a barrel 13 providing an extension of the chamber 11 and in the free end of this barrel is positioned a check valve comprising a plug 14 having a vent 15 normally closed by a spring pressed ball 16. In the other end of the chamber 10 is a port 17 and a communicating recess 18, and check valve controlling the port 17.

As shown, this valve comprises a spring pressed ball 19 positioned in the recess and a retaining plug 20; the ball normally closes the port 17 and leading from the recess 18 is a passage 21 communicating with the auxiliary chamber 11. The auxiliary chamber 11 has threaded into one end thereof a plug 22 axially bored as indicated at 23 and threaded on the plug is a nozzle 24, the nozzle having arranged therein a valve comprising a spring pressed ball 25 adapted to normally close the bore in the plug.

The auxiliary chamber 11 has positioned therein for reciprocation a plunger 26 provided with a rack 27 and an operating handle 28. The boss 12 on the auxiliary chamber 11 is transversely bored to receive a shaft 29 on which is keyed a pinion 30, the pinion being in mesh with the rack 27 on the plunger 26 and keyed upon one end of the shaft 29 is

a spiral gear 31, the object of which will hereinafter appear.

Supported for oscillation on the shaft 29 is an arm 32. This arm is yieldingly depressed by a spring actuated plunger 33 positioned in the boss 12 and made adjustable relative to the chambers by a set screw 34. Mounted for rotation in the free end of the arm is a roller 35 and positioned above the roller is a transverse bore having journaled therein a shaft 36. The shaft 36 has keyed on one end a spool guide 37, the face of which is covered with rubber or any suitable material which will prevent slipping and keyed upon the other end of the shaft is a worm gear 38.

A shaft 39 is supported in suitable brackets on the arm 32. This shaft is parallel to the arm 32 and keyed on one end thereof is a gear 40 in mesh with the worm gear 38 and mounted for rotation on the other end of this shaft is a spiral gear 41 in mesh with the spiral gear 31 on the transverse shaft 29. The gear 41 carries one member 42 of a clutch, the other member 43 of which is mounted for reciprocation on the shaft 39 and is normally held in engagement with the member 42 by a spring 44.

In operation, liquid paint is placed in the chamber 10 and the barrel 13 and the plug 14 is threaded in the end of the barrel. Upon withdrawing the piston 26 by the handle 28 paint will be drawn from the chamber 10 through the port 17 and the passage 21 into the auxiliary chamber 11. The suction created by pulling outwardly on the piston 26 is sufficient to open the valves in the chamber 10 and the barrel 13 and these valves are immediately seated or closed upon discontinuance of the suction or the outward movement of the piston 26.

When adjusting the instrument to the surface to be striped the nozzle is either adjusted by the set screw 34, or pressed in position against the resistance of the arm 32. Upon drawing the instrument over the surface to be striped the guide roller 35 rotates the worm gear 38 which through the shaft 39, gear 40 and spiral gear 41 drives the spiral gear 31 and hence the shaft 29 carrying the pinion 30. The pinion 30 meshes with the rack 27 on the piston 26 and moves the piston forward in the auxiliary chamber 11 to eject paint through the nozzle 24 against the action of the spring pressed ball 25. During this operation the port 17 is closed by the spring pressed ball 19 to prevent back pressure in the chamber 10 and the barrel 13. Assuming that at the end of the stroke the piston 26 has moved sufficiently to eject all of the contents of the auxiliary cylinder 11, or only a portion thereof, according to the length of the stroke of the piston and that it again becomes necessary or desirable to replenish or refill the auxiliary chamber 11, the

clutch is disengaged and the piston 26 is drawn outwardly by the handle 28 whereupon paint is again drawn from the main supply chamber 10 and the barrel 13 through the port 17 and passage 21 to the auxiliary chamber 11 whereupon the clutch is thrown into engagement for the next operation.

Although this invention has been described in connection with certain specific embodiments, the principles involved are susceptible of numerous other applications that will readily occur to persons skilled in the art. The invention is, therefore, to be limited only as indicated by the scope of the appended claims.

Having thus described the various features of my invention, what I claim as new and desire to secure by Letters Patent is:

1. A painting instrument comprising a chamber having a nozzle, a reciprocating piston positioned in the chamber, an oscillatory arm on the chamber, a rotatable guide on the arm and means connecting the guide with the piston for operating the piston.

2. A painting instrument comprising a chamber, an auxiliary chamber communicating therewith, a nozzle for the auxiliary chamber, a feeding means in the auxiliary chamber, means for actuating the feeding means in one direction and other means for actuating the feeding means in the opposite direction.

3. A painting instrument comprising a chamber, a valve in each end of the chamber, an auxiliary chamber communicating with the other chamber through one of the valves, a nozzle in one end of the auxiliary chamber, a piston in the auxiliary chamber, means for operating the piston to open the valves when the piston is moved in one direction and to seat the valve between the chambers when the piston is operated in the other direction, a rotatable guide for the instrument and means associated therewith for moving the piston in one direction.

4. A painting instrument comprising a chamber, an arm pivoted on the chamber, a nozzle fixed to the chamber, a rotatable guide member on the free end of the arm and means actuated by the guide member for effecting a positive feed of paint through the nozzle.

5. A painting instrument comprising a chamber, a nozzle communicating therewith, a piston positioned in the chamber, a spring pressed arm pivoted to the chamber, a rotatable guide on the free end of the arm, means connecting the guide with the piston for moving the piston in one direction including a clutch for disengaging the operating means.

6. A painting instrument comprising a chamber, a nozzle communicating with the chamber, a valve normally closing the nozzle, a reciprocating piston in the chamber, a spring pressed arm pivoted on the chamber,

- means for adjusting the arm relative to the nozzle, a guide in the free end of the arm, a driving means between the guide and the pinion including a clutch mechanism for disengaging the driving means.
5. 7. A painting instrument comprising a chamber, an auxiliary chamber parallel to the chamber and a port between the chambers, a valve for normally closing the port, a nozzle in one end of the auxiliary chamber, a valve 10 for normally closing the nozzle, a reciprocating piston in the auxiliary chamber, a rack on the reciprocating piston, a spring pressed arm on the auxiliary chamber, a rotatable guide in the free end of the spring pressed arm, a shaft supported by the spring pressed arm, gears on the shaft connecting the rotatable guide with the reciprocating piston including a clutch. 70
10. 8. A painting instrument comprising a chamber, an auxiliary chamber parallel thereto and a port connecting the chambers, a valve adapted to normally close the port, a nozzle in one end of the auxiliary chamber, a valve 15 in the nozzle for normally closing the nozzle, a reciprocating piston positioned in the auxiliary chamber, a rack formed upon the reciprocating piston, a spring pressed pivoted arm on the auxiliary chamber, means for adjusting the arm, a rotatable guide on 80 the free end of the arm, a shaft supported by the arm, gears connecting the shaft with the rotatable guide, a second set of gears connecting the shaft with the rack, including a clutch for disengaging the gears and means for moving the piston outwardly upon disengagement of the second set of gears. 85
20. 9. A painting instrument adapted for movement over the work, comprising a chamber, an auxiliary chamber connected therewith, a nozzle associated with the auxiliary chamber, a plunger in the auxiliary chamber, and means for actuating the plunger to discharge fluid from the auxiliary chamber in a flow of uniform volume per unit area of work. 90
25. 10. A painting instrument comprising a chamber, a nozzle communicating with the chamber, a plunger in the chamber, a rotatable guide, and means connecting the guide 95 with the plunger, at points intermediate the ends of the plunger, for actuating the plunger in one direction to discharge fluid through the nozzle. 100
30. 11. In a painting instrument comprising a fluid containing chamber, a driving member, and positive feeding means adapted, when moved in one direction, to feed fluid to the work, a clutch member between the driving member and the feeding means adapted to 105 prevent movement by the driving member of the feeding means in the other direction. 110
35. 12. A painting instrument comprising a fluid containing chamber, a nozzle connected with the chamber, a fluid feeding mechanism, and a rotatable guide for actuating the feed- 115
- ing mechanism, the guide being adjustably mounted with reference to the chamber. 120
40. 13. A painting instrument comprising a fluid containing chamber, a nozzle connected with the chamber, a fluid feeding device associated with the chamber, an arm pivotally mounted on the chamber, a rotatable guide on the arm, and means, engaged with the arm, for operatively connecting the guide with the fluid feeding device to discharge fluid 125 through the nozzle. 130
45. 14. A painting instrument comprising a fluid containing chamber, a nozzle connected with the chamber, a fluid feeding device for the chamber, to cause discharge of the fluid through the nozzle, and a driving means adapted to be discontinuously engaged with the fluid feeding device. 135
50. 15. A painting instrument comprising a main chamber for holding a supply of paint, an auxiliary chamber for holding a limited supply of paint, a nozzle connected to the auxiliary chamber, a plunger in the auxiliary chamber, a driving means operatively engaged with the plunger to feed paint 140 through the nozzle, and means for disengaging the driving means from the plunger in order that the plunger may be withdrawn, thereby drawing paint from the main chamber into the auxiliary chamber. 145
55. 16. A painting instrument comprising a paint containing chamber, a nozzle connected with the chamber, a plunger in the chamber, a driving member associated with the chamber, and means outside the chamber for connecting the driving member and the plunger. 150
60. 17. In a painting instrument for applying a stripe upon surfaces, a casing structure having a passage therein, a paint reservoir communicating with one end of the passage, a nozzle extending from the casing structure and communicating with the other end of the passage, pump means in the casing intermediate the ends of the passage, an oscillatory arm on the casing, a roller rotatably mounted on the free end of the arm, and a driving connection between the roller and the pump means. 155
65. 18. In a painting instrument for applying a stripe to surfaces, a casing structure having a passage therein, a paint reservoir communicating with one end of the passage, a nozzle extending from the casing and communicating with the other end of the passage, pump means in the casing intermediate the ends of the passage, a spring-pressed arm pivoted to the casing, a rotatable guide member on the free end of the arm, and means connecting the guide member with the pump 160 means for actuating the same. 165
70. 19. In a painting instrument for applying a stripe to surfaces, a casing structure having a passage therein, a paint reservoir communicating with one end of the passage, a 170

nozzle extending from the casing and communicating with the other end of the passage, pump means in the casing intermediate the ends of the passage, a guide roller associated with the casing, another guide roller associated with the casing and spaced laterally in an offset relation to the other guide roller, the outlet end of said nozzle being maintained against the surface to be striped when the rollers engage therewith and the casing is tilted at a predetermined angle, and driving means between one of the guide rollers and the pump.

In testimony whereof I affix my signature.
